UNITED STATES PATENT OFFICE.

JEAN JULES MARIE ANTOINE EUGÈNE SCHNEIDER, OF PARIS, FRANCE, ASSIGNOR TO SCHNEIDER & CIE., OF PARIS, FRANCE, A LIMITED JOINT STOCK COMPANY OF FRANCE.

ARMING OF AEROPLANES.

Application filed August 14, 1922. Serial No. 581,835.

To all whom it may concern:

Be it known that I, JEAN JULES MARIE ANTOINE EUGÈNE SCHNEIDER, a citizen of the Republic of France, residing at Paris, France, have invented new and useful Improvements in the Arming of Aeroplanes, which invention is fully set forth in the following specification.

The present invention relates to the invention for which an application was filed by me on Aug. 14, 1922 and numbered 581,834, and it relates more particularly to an improvement in the apparatus for arming aeroplanes, as described with reference to Figs. 14, 15 and 16 of my said earlier application, wherein the gun barrel is mounted in a stationary turret constituting a supporting framework for the cradle in which the gun barrel is swivelled for training the gun along an axis at right angles to the axis of the gun barrel, and in a frame which in its turn carries elevating trunnions for which bearings are provided in the lateral frame-plates of the said framework fixed to the said stationary turret.

The improved apparatus of the present invention is illustrated in the accompanying drawings wherein:—

Figs. 1, 2 and 3 are respectively a longitudinal elevation, a plan and a section taken along the line 3—3 of Fig. 1 of a preferred constructural example of the said improved apparatus.

For the sake of greater simplicity, it is assumed in Figs. 2 and 3 that the gun barrel and its cradle have been brought into a horizontal position which they cannot occupy in practice.

In these figures, C is a turret upon which is formed a rolling track *c* for rollers *n*, the pins *n'* of which are mounted in the transverse sides of the carriage I. In this frame there is mounted so as to be capable of pivoting by means of horizontal trunnions F', a frame P in which the gun cradle F can swivel by means of trunnions *p* arranged along an axis at right angles to the axis of the gun barrel.

The elevation of the gun is effected in this improved apparatus by a rocking motion of the frame P around the axis of the trunnions P'. For this purpose the frame P carries toothed sectors *P*² meshing each with a pinion *P*³. These two pinions are fixed on a shaft *p*³ journalled in the carriage I and can

be driven by means of gearing *P*⁴, *P*⁵ actuated by means of a hand-wheel *P*⁶.

Large angular movements of the gun barrel relatively to the longitudinal axial plane of the aeroplane, are produced by rotating the carriage I along the rolling track *c*, for instance by means of gearing comprising, on the carriage I, a helical wheel sector I', meshing with a worm I² journalled in a fixed bearing I³ and actuated by means of a hand wheel I⁴.

As shown in the drawings, the transverse sides of the carriage I, which carry the pins *n'* arranged along radii of the rolling tracks *c*, are formed with rims or flanges by means of which they engage with the under-sides of the said tracks.

The holding and guiding of the gun during its angular movements along the tracks *c* may further be assured, for instance, by means of a roller *i'* mounted on an arm *i*² projecting from one of the longitudinal sides of the frame I; the said roller being engaged in an arc-shaped slot-guide *c'* rigidly fixed to the turret or to the rolling tracks *c*.

The angular training movements of small amplitude of the gun barrel which has been previously moved along the circular tracks *c*, are produced by swivelling the gun cradle around the axis of the trunnions P. The gun cradle F is provided with a worm wheel sector *f* meshing with a worm *f'* journalled in bearings carried by the toothed sectors F².

The shaft of the worm *f'* carries a bevelled pinion *f*² meshing with a pinion *f*³, the bearing of which is carried by one of the sectors *p*² and which is actuated by means of a flexible shaft *f*⁴ by means of a hand wheel *f*⁵.

Having now particularly described and ascertained the nature of my said invention and in what manner the same is to be performed I declare that what I claim is:—

1. Means for arming aircraft comprising a turret, a rolling carriage mounted on said turret, a frame horizontally trunnioned on said carriage, a cradle vertically trunnioned on said frame, and a gun carried by said cradle.

2. Means for arming aircraft comprising a stationary turret provided with a track, a rolling carriage mounted on said track, a frame horizontally trunnioned on said carriage, a cradle vertically trunnioned on said frame, and a gun carried by said cradle.

3. Means for arming aircraft comprising, a stationary turret having a substantially circular track disposed above the bottom thereof, a rolling carriage mounted on said track, a frame horizontally trunnioned on said carriage, a cradle vertically trunnioned on said frame, and a gun carried by said cradle.
4. In a gun mount for aircraft, a stationary turret, a rolling carriage mounted thereon, a frame horizontally trunnioned on said carriage, a gun cradle vertically trunnioned on said frame, means for rolling said carriage, means for elevating said frame, and means for training said cradle.
5. In a gun mount for aircraft, a stationary turret provided with a track substantially concentric thereto, a carriage provided with rollers in engagement with said track, a frame horizontally trunnioned on
6. In a gun mount for aircraft, a stationary turret having a track concentric therewith, a gun carriage having rollers in engagement with said track, means for rolling said carriage on said track, and means for holding and guiding said carriage during its rolling movement, said means comprising a slotted guide on one of said first-named elements and an arm on the other of said first-named elements having rollers engaged in said slotted guide. 25
7. In a gun mount for aircraft, a stationary turret having a track concentric therewith, a gun carriage having rollers in engagement with said track, means for rolling said carriage on said track, and means for holding and guiding said carriage during its 30 rolling movement, said means comprising a slotted guide on one of said first-named elements and an arm on the other of said first-named elements having rollers engaged in said slotted guide. 35

Dated this 6th day of July, 1922.

In testimony whereof I have signed this specification.

JEAN JULES MARIE ANTOINE EUGÈNE SCHNEIDER.
